UNITED STATES PATENT OFFICE.

WARREN C. JOHNSON, OF OSKALOOSA, IOWA.

WASHING-MACHINE.

SPECIFICATION forming part of Letters Patent No. 244,615, dated July 19, 1881.

Application filed April 15, 1880. (Model.)

To all whom it may concern:

Be it known that I, WARREN C. JOHNSON, of Oskaloosa, in the county of Mahaska and State of Iowa, have invented certain new and useful Improvements in Washing-Machines; and I do hereby declare that the following is a full, clear, and exact description of the invention, which will enable others skilled in the art to which it appertains to make and use the same, reference being had to the accompanying drawings, which form a part of this specification.

My invention relates to improvements pertaining to washing-machines; and the novelty consists in the construction and arrangement of parts, as will be more fully hereinafter set forth, and more specifically pointed out in the claim.

A great desideratum in this, as in other classes of machines, is to produce an efficient device cheaply, simple, of few pieces, and having less liability to get out of order and useless for the purpose sought to be attained.

To this end my device consists, essentially, of four pieces—viz., a supporting-frame, a driving-wheel, and a geared operating-shaft with an attached stirrer or agitator—the connecting pins, nuts, &c., being of well-known construction.

With this object in view I cast in one piece of metal a cap to fit over and be secured to the top of the vessel, a single standard having journal-bearings for a vertical and a horizontal shaft, a standard to operate therewith, and a downwardly-projecting sleeve to receive and give extended journal-bearings for a vertical operating-shaft. A beveled gear upon a horizontal shaft meshes with a bevel-gear upon a vertical shaft, the latter of which works in a sleeve and is provided with a key which operates in a semi-cylindrical recess in a stirrer-plate having downwardly-projecting arms, to which are attached the portable stirring-arms. (Not shown.) This stirrer-plate is held in locked position with the key upon a vertical shaft by a thread-and-nut connection beneath.

In the drawings, Figure 1 represents a front elevation; Fig. 2, a side elevation, partially in section, and Fig. 3 a top-plan view.

Referring to the drawings, A represents the cap or plate, having a downwardly-projecting

sleeve, B, and perforated at a' to receive screws by which it is attached or secured to the tub or vessel. (Not shown.) Cast in one therewith is an elbow-arm, a, having a journal-bearing, A', 55 to receive the upper end of the vertical stirrer-shaft, which will be hereinafter explained. From this elbow portion a extends a vertical standard, F', having a journal-bearing, f, for one end of a horizontal shaft, e, to which is 60 keyed, by a thumb-screw, the sleeve e' of a beveled gear-wheel E, as shown.

F represents a standard, cast in one with the cap A, and having a journal-bearing, f', to receive the other end of shaft e. 65

It will thus be understood that the cap A, sleeve B, elbow-arm a, standards F F', and journal-bearings A' and f f' are all cast in one piece of metal, thus avoiding joints, which are liable to become loose and get out of order, and also being cheaper of manufacture. The wheel B is provided for more than half of its surface with cogs to form a bevel-gear, and also with laterally-extending flanges, which extend from the periphery inward to a line on a plane with the axis. These flanges have smooth or rounded surfaces, and protect the nut which secures the handle, which is adjustable in the slot h, from catching the clothes of persons passing. 75

C represents a vertical shaft journaled within the sleeve B, and also at A' in the elbow-arm a. Securely keyed upon it is a beveled wheel, D, which meshes with the wheel E, and it is provided with a diametrical cross-pin, C', which rests in a semi-cylindrical groove or recess, d, 85 in a plate or stirrer, D', having downwardly-extending ribs d', as shown. The shaft C is provided with a screw-thread, and a nut, C², forces the stirrer-plate upward until the pin C' is engaged in the recess d and forces the shaft C and stirrer to oscillate together. Cast in one with the stirrer D' is a projection, b, which rests upon proper washers above the nut. 90

This invention is designed as an improvement upon the device shown in Patent No. 61,343, of 1867, and the construction therein shown is not sought to be covered in this application.

I deem the frame furnishing four journal-bearings, and a convenient cap, and also cast in one piece of metal, as shown and described, 100

important. I also place importance upon the means and manner of securing the stirrer to the vertical shaft.

What I claim as new is—

5 The stirrer D', having semi-cylindrical recess *d* and arms *d'*, the pin *c'* and nut *C'*, the cap *A*, having sleeve *B*, standards *F F'*, elbow-arm *a* and bearings *A' f f'*, said cap, sleeve, and standards cast in one piece, and the whole 10 constructed, arranged, and combined to oper-

ate with the operating-gear as and for the purposes set forth.

In testimony that I claim the foregoing as my own I have hereto affixed my signature 15 in presence of two witnesses.

WARREN C. JOHNSON.
